UNITED STATES PATENT OFFICE.

GEORGE H. CHALK, OF PHILADELPHIA, PENNSYLVANIA.

WIRE MOTION FOR LOOMS.

Application filed May 27, 1921. Serial No. 473,039.

To all whom it may concern:

Be it known that I, GEORGE H. CHALK, a citizen of the United States, residing at Philadelphia, in the county of Philadelphia and State of Pennsylvania, have invented certain new and useful Improvements in Wire Motions for Looms, of which the following is a specification.

My invention relates to wire motions for 10 looms, that is to say, to mechanism for actuating the pile forming wires in looms for weaving pile fabrics such as tapestries, wiltons, velvets and the like.

Heretofore, in the operation of looms employing wires for forming the pile in the cloth, it frequently happened that the wires would be broken off and the eye portions thereof would remain in the holder for inserting the wire in the shed, so that the next 20 wire would be prevented from being engaged by the holder, and, until the broken off eye was removed from the holder, the loom would continue to operate and weave a defective fabric thus resulting in great loss, as well also frequently causing damage to 25 the loom itself. In other instances, the spring tension of the gripping device of the holder which is employed to hold the eye of the wire in the holder would sometimes be sufficient to improperly pull the wire out of 30 the fabric, which would also cause a defective pick in the cloth, rendering the same unsalable.

The object, therefore, of my present invention is to provide in a loom of the character described means for positively insuring the removal of the eye portions of the wires from the holder, to thereby eliminate the damage and loss caused when the same 40 are improperly held therein.

The nature and characteristic features of my invention will be more readily understood from the following description, taken in connection with the accompanying drawings forming part hereof, in which—

Figure 1 is a front elevation, certain parts being broken away, of a portion of a wire motion loom having a device embodying the main features of my invention mounted 50 therein;

Fig. 2 is a top or plan view thereof; and

Fig. 3 is a perspective view illustrating the device embodying the main features of my present invention with certain coacting parts of the loom shown in the positions assumed as the device of my present inven-

tion is engaging the eye of the wire for the purpose of removing the same from the holder.

Referring to the drawings, my invention 60 is therein shown as applied to a wire motion loom of a well known type, but it will, of course, be understood that the same is equally applicable to looms employing other types of mechanism for manipulating the 65 pile forming wires in the loom during the formation of the cloth.

In the loom there shown 5 are the pile forming wires having enlarged end portions 6 provided with eyes 7. The eyes 7 70 are adapted to be engaged by a hook member 8 at proper times for the purpose of removing the same from the cloth after the pile is formed and a sufficient number of picks have been beaten up to maintain the 75 formation of the pile. The hook member 8 is carried by a cross head 9, which is mounted upon a stationary rail or track 10 and is adapted to be reciprocated thereon. The means for reciprocating the cross head 9 80 may comprise a link member 11, one end of which is pivoted to the cross head 9 and the other end of which is pivotally connected to the free end of a lever 12, which lever is pivoted at its other end as at 13, to a bracket 85 14 carried by the framework of the loom. Motion is imparted to the lever 12 by means of a connecting rod 15 one end of which is pivotally connected to the lever 12 midway 90 its extremities and the other end of which is pivoted to an adjustable crank member 16, which is rotated by any suitable mechanism in synchronism with the operation of the loom. The mechanism above described is so constructed and arranged that at each 95 reciprocation of the cross head 9 one of the eyes 7 of a pile forming wire 5 will be engaged by the hook member 8, and when the cross head 9 is retracted, the wire will be withdrawn from the cloth.

Arranged above the wire extracting mechanism above described, and suitably supported by the framework of the loom, is a horizontal shaft 18, upon which are secured depending arms 19, which carry at 100 their lower ends a horizontal track or rail 20, which has a swinging motion about the axis of the supporting shaft 18. The track or rail 20 serves as a guide for the reciprocation of the holder 21, which is mounted 105 thereon, the reciprocation being effected by means of a lever 22, one end of which is

in slotted engagement with a stud 23 carried by the hopper 21, and the other end of which is pivoted, as at 24, to the end of a supporting arm 25, which also is carried by the shaft 18 which carries the track supporting arms 19. The lever 22 is actuated by means of a connecting rod 26, which is pivoted at one end to the lever 22, midway its extremities, and pivoted at its other end to one end of a bell crank lever 27 which is pivoted, as at 28, to the framework of the loom. The other end of the bell crank lever 27 carries a roller 29 which is engaged by a cam 30, which is also rotated by any suitable mechanism in synchronism with the operation of the loom. The construction and arrangement of the foregoing mechanism is such that the holder 21 will be reciprocated at proper intervals and will also be moved sidewise, for a purpose to be presently explained.

The holder 21 is provided with means for engaging and gripping the enlarged portion 6 at the end of each pile forming wire 5, as clearly shown in Fig. 3 of the drawings. The particular arrangement there shown comprises the provision at the lower end of the holder 21 of a turned over portion 32, forming a groove into which the lower edge of the enlarged portion 6 of the wire 5 is adapted to enter, and above this groove there is mounted a pivoted member 33, also provided on its under face with a groove in which the top margin of the enlarged portion 6 of the wire 5 is adapted to be seated. The pivoted member 33 is engaged by one end of a spring 34, the other end of which is secured to the plate of the holder 21, as at 35, the arrangement being such that the tension of the spring 34 will cause the pivoted member 33 to resiliently grip the enlarged end 6 of the wire 5.

The construction and arrangement of the holder and its actuating parts is such that after each wire is withdrawn from the cloth by means of the withdrawing mechanism first above described, and is retracted sufficiently to entirely withdraw the same from the cloth, the enlarged end 6 of the wire 5 will be received by the resilient gripping mechanism above described, and then through the swinging of the track 20 about the axis of the shaft 18, the same will be carried towards the rear of the loom, after which the holder will again be caused to reciprocate on its track 20 to insert the wire in the shed, so that the same may be beaten up by the reed 37 and thus form the next pile in the cloth.

All of the mechanism above described is well known to those skilled in the art, and the description thereof is only necessary in order that the novel device of my present invention may be more readily understood.

In the operation of the wire motion above de-

scribed, it frequently occurs that the wire will be broken off at some point between its extremities, or, as most usually occurs, near the enlarged portion 6, and when the holder 21 is retracted after the wire is inserted into the weave, the broken portion will be carried back by the holder, and when the next wire is withdrawn from the cloth by the extracting hook 8, the holder will not be in a condition to receive the same, and damage will often result to the mechanism of the loom, or in any event, the next wire will not be carried forward and inserted in the shed in the proper manner, as a result of which a defect in the weave will occur which will render the cloth unsalable. It sometimes also occurs that the spring tension on the pivoted member 33 will be too strong to permit the enlarged end 6 to be freed when the holder is withdrawn, and the wire will be improperly pulled out of the cloth, thus also causing defects in the weave and disarrangement of the mechanism.

To obviate these defects in the operation of wire motions of the type above described, there is provided a device 40, shown in perspective in Fig. 3 of the drawings, for positively insuring the withdrawal of the eye portion 6 of the wire from the holder in the event of the wire breaking or not being held against withdrawal by the holder. This device 40 comprises a bracket 41, which is secured to the breast rail or other suitable part of the loom and is provided on its extending portion with a channel 42, in which is mounted a bar 43. The forward end of the bar 43 is suitably bent and shaped so as to engage the eye portion 6 of the wire 5 after the same is inserted in the shed by the reciprocation of the holder 21 on its track 20, and, when the holder 21 is retracted, the engagement of the point 44 of the bar 43 with the eye 7 or other part of the enlarged portion 6 of the wire 5 will insure that the same will be positively extracted from the gripping portion of the holder 21. In order that the point 44 of the bar 43 may be permitted to ride into engagement with the eye portion 6, the same is capable of slight motion in the channel 42 of the extending portion of the bracket 40, but the bar 43 is normally held in its forward position by means of a spring 45, which is connected at one end to a pin 46 carried on the under side of the bracket 41, and at its other end to a downwardly extending portion 47 of the rear end of the bar 43, which passes through a suitable slot 48 in the bracket 41, as clearly shown in Fig. 3 of the drawings.

It should be noted that in the ordinary functioning of the wire motion the bind of the warp threads of the fabric will be sufficient to hold the wire 5 and cause the eye portion 6 thereof to be freed from the holder 21, and the extracting device 40 of my pres-

ent invention will not be called into play. If, however, the weft thread in the next pick should run out or break, it will be readily understood by those skilled in the art that 5 no binding effect on the wire will take place, and if this occurs before the return movement of the holder begins, the wire is likely to be withdrawn by the holder, and as the wire has been beaten up close to the fabric, 10 the knife on the end of the wire will cut through the warp ends with the consequent great damage resulting therefrom.

When, therefore, the eye portion 6 is not withdrawn from the holder 21 in the normal manner, the point 44 of the bar 43 will engage the eye portion 6 of the wire 5, either at the heel thereof, or in the eye 7 as shown in Fig. 3 of the drawings, and the wire will thereby be prevented from being withdrawn 20 and "cut outs" in the fabric will be obviated.

It should also be noted that the point 44 of the bar 43 is located beyond the normal line of the ends of the eye portions 6 of the wires 5 in the fabric, so that the ordinary action 25 of the wires is not interfered with, but in the event, that, in the return movement of the holder, an eye portion 6 of one of the wires remains therein, then the point 44 will act to extract the same from the holder. As this 30 action will only occur when something is wrong in the operation of the loom, it will, of course, always be necessary to stop the loom to make the required corrections, at which time the wire, or rather the eye portion 35 thereof, which has been engaged by the point 44, may be manually disengaged therefrom, and properly arranged as may be required.

It will be seen that by the foregoing arrangement, there is provided means for positively insuring the extraction of the eye portion of the pile forming wire from the gripping mechanism of the holder when the holder is retracted after having delivered 45 the wire into the shed, which mechanism will operate to free the eye portion of the wire independently of the gripping tension of the warp upon the pile forming wire, and which will operate even when the wire is broken off 50 close to the eye portion.

Having thus described the nature and characteristic features of my invention, what I claim as new and desire to secure by Letters Patent, is:

55 1. In a pile fabric loom, the combination with the pile forming wires having enlarged eye portions and a reciprocating holder adapted to engage and grip said eye portions and to insert the wires into the 60 shed, of means adapted to positively engage the eye portion of the wire and retain the same against retraction by the holder in the event that the same is not normally withdrawn therefrom.

65 2. In a pile fabric loom, the combina-

tion with the pile forming wires having enlarged eye portions and a reciprocating holder adapted to engage and grip said eye portions and to insert the wires into the shed, of means for detaching the eye portions of the wires from the holder in the event that the same are not normally withdrawn therefrom, said means including a member carried by a stationary portion of the loom having one end adapted to encounter and engage the eye portion of the wire and retain the same against retraction by the holder. 70

3. In a pile fabric loom, the combination with the pile forming wires having enlarged eye portions and a holder adapted to engage said eye portions and to insert the wires into the shed, of means for detaching the eye portions of the wires from the holder in the event that the same are not normally withdrawn therefrom, said means including a slideable member carried by a stationary portion of the loom having a pointed end adapted to encounter and engage the eye portion of the wire and retain the same against retraction by the holder, and a spring for normally maintaining said member in its forward position. 80

4. In a pile fabric loom, the combination with the pile forming wires having enlarged eye portions and a holder adapted to engage said eye portions and to insert the wires into the shed, of means for detaching the eye portions of the wires from the holder in the event that the same are not normally withdrawn therefrom, said means comprising a bracket mounted on a stationary portion of the loom, and a bar carried by said bracket having a pointed end adapted to encounter and engage the eye portion of the wire and retain the same against retraction by the holder. 90

5. In a pile fabric loom, the combination with the pile forming wires having enlarged eye portions and a holder adapted to engage said eye portions and to insert the wires into the shed, of means for detaching the eye portions of the wires from the holder in the event that the same are not normally withdrawn therefrom, said means comprising a bracket mounted on a stationary portion of the loom, and a bar slidably carried by said bracket, said bar having a pointed end adapted to encounter and engage the eye portion of the wire and retain the same against retraction by the holder. 100

6. In a pile fabric loom, the combination with the pile forming wires having enlarged eye portions and a holder adapted to engage said eye portions and to insert the wires into the shed, of means for detaching the eye portions of the wires from the holder in the event that the same are not normally withdrawn therefrom, said means comprising a bracket mounted on a station- 110

ary portion of the loom, a bar slidably carried by said bracket, said bar having a pointed end adapted to encounter and engage the eye portion of the wire and retain the same against retraction by the holder, and means for normally maintaining said bar in its forward position.

7. In a pile fabric loom, the combination with the pile forming wires having enlarged eye portions and a holder adapted to engage said eye portions and to insert the wires into the shed, of means for detaching the eye portions of the wires from the holder

in the event that the same are not normally withdrawn therefrom; said means comprising a bracket mounted on a stationary portion of the loom, a bar slidably carried by said bracket, said bar having a pointed end adapted to encounter and engage the eye portion of the wire and retain the same against retraction by the holder, and a spring for normally maintaining said bar in its forward position.

In testimony whereof, I have hereunto signed my name.

GEORGE H. CHALK.
